UNITED STATES PATENT OFFICE.

ALEXANDER F. WINTERS AND BASIL R. CRAMPTON, OF GRAND RAPIDS, MICHIGAN.

REVERSIBLE LATCH.

Application filed September 20, 1926. Serial No. 136,399.

This invention relates to improvements in reversible latches particularly intended for use on refrigerator doors.

The advantage of a reversible latch is that the same latch may be used on a door swinging from either the right or left side. When such a latch is used to equip refrigerators at the factories it is only necessary to have a supply of latches of one kind on hand. The necessity of determining the number for use on right hand doors and for use on left hand doors is eliminated. The same is true in merchandising establishments. It is only necessary to carry one kind of latch and not a double supply and the possibility of mistakes in selling the wrong latch is eliminated. Furthermore the manufacture of a latch of this type is simplified because it is only necessary to provide dies of one kind instead of a double set of dies for right and left hand latches.

The latch provided by this invention is designed to be simply and cheaply made and to be positive and accurate in its operation and strong and substantial in structure. The latch is provided with various new and useful features of construction and arrangement as hereinafter more fully described and pointed out in the claims, reference being had to the accompanying drawings, in which

Fig. 1 is a front view of the latch and keeper applied to a door with the top of the casing of the latch removed.

Fig. 2 is a section of the same substantially on the line 2—2 of Fig. 1.

Fig. 3 is a section of the same on the line 3—3 of Fig. 2.

Fig. 4 is a view of the same description as Fig. 1 showing the latch bar moved to unlatched position and retained in such position.

Fig. 5 is a front view of the latch and keeper showing the latch bar is unlatched position and removed from the keeper, and

Fig. 6 is a fragmentary perspective of a part of the latch bar and the actuating levers in partially disassembled position.

The latch embodying this invention includes a casing having a body portion 1 and flanges 2 extending therefrom through which screws 3 are passed to attach it to the door. The casing has a bottom 4 of sheet metal at the forward edge of which is a ledge 5 preferably formed by turning an integral part of the bottom member backward upon itself.

The latch lever 6 extends through openings 7 and 8 in the respective front and rear sides of the casing and is provided at its rear end with a handle portion 9. The forward extension 10 of the latch lever is inclined inwardly at its respective edges where it engages the keeper. The latch lever is preferably stamped from heavy sheet metal, it being so designed that this method of manufacture is possible.

The latch lever is pivoted in the casing on a pin 11 which extends through a hole provided in the latch lever, this pin being formed on a plate 12 which lies against the top of the casing and extends a short distance down the rear side thereof and is held in place by turning an ear 13 of the casing around it. The latch lever must oscillate about the pivot pin 11 and must also have a slight rocking movement thereon to enable its forward end to move outward to pass over the ledge 5, and for this purpose the opening in the lever through which the pin 11 extends is large enough to permit such rocking movement.

The latch lever is yieldably retained in central or horizontal position by means of two actuating levers 14 which are pivoted in superimposed relation upon the pin 11. These levers extend at the respective sides of the latch lever approximately parallel therewith and both ways from the pivot pin. The rear extension of each lever has a downturned finger 15 to engage its respective side of the latch lever while the forward end of each lever is provided with a downturned leg 16 normally engaging the inner side of the casing 1. A compression spring 17 is interposed between the forward ends of the respective levers and yieldably separates them causing the legs 16 to engage the respective sides of the casing 1 and the fingers 15 to engage the respective sides of the latch lever to hold it in central horizontal position.

When the latch lever is oscillated in either direction from the horizontal, as shown in Fig. 4, one of the actuating levers 14 will be moved by engagement of its finger 15 with one side of the latch lever and its forward end will be moved toward the forward end of the opposite lever 14 which is prevented from moving by engagement with the casing 1 and the spring 17 will be compressed. The tendency of the spring is to return the lever to mid position or

horizontal position when it is released and this same action occurs when the lever is moved in the opposite direction from the horizontal, in which case the opposite lever 5 14 is moved.

When the latch lever is moved to its extreme position in either direction from the horizontal, which is unlatched position, it will be retained by lodging against one edge 10 of the ledge 5, the lever rocking slightly toward the bottom plate 4 to thus lodge against the ledge. This rocking movement is partly performed by the normal outward pull by the operator who grasps the handle 15 portion 9 to operate the lever but the rocking movement is assured and made more positive by action of the spring 17 which is so designed that it bows downwardly between its ends, the central portion bearing 20 against the upper side of the latch lever which is flattened at 18.

In this unlatched position the forward end 10 of the latch lever is freed from the keeper 19 and the door may be opened and the latch lever will normally be retained in this unlatched position. When the door is closed the forward end 10 of the latch lever strikes an unlatching extension 20 formed on the base 21 of the keeper and dislodges 30 it from the ledge 5 whereupon the action of the spring 17 moves the lever to horizontal or latched position, its forward end catching under the keeper 19. The outer end of the keeper 19 is inclined at 22 so that in case the latch lever has become dislodged and returned to normal position while the door is open its forward end will engage the inclined surface of the keeper as the door is closed and move it by cam action 40 around the keeper and permit it to spring into place under the keeper to latched position.

It will be seen that both the latch and the keeper are reversible for doors swinging in opposite directions. The drawings illustrate the latch and keeper applied to a door hung at its right hand edge. If the door to which the latch is to be applied is hung 45 at the left hand edge the latch is simply inverted while the keeper is of the same shape on both sides and is simply placed without being inverted or its position otherwise changed, adjacent the edge of the door to be engaged by the end of the latch lever.

By pivoting the actuating levers 14 on the pin 11 which is also the pivot for the latch lever, the actuating levers simply swing with movement of the latch lever and have 60 no sliding engagement therewith, thus eliminating friction and wear between these parts and also cheapening the structure by eliminating extra pivots for the actuating levers.

We claim:

65 1. A reversible latch comprising a piv-

oted latch lever, and means for yieldably holding the latch lever in central position, said means including two spring actuated pivoted levers engaging opposite sides of said latch lever and exerting thrusts against 70 the latch lever in opposite directions.

2. A reversible latch comprising a pivoted latch lever, a pivoted actuating lever located at and engaging each respective side of said latch lever, and a single spring interposed between said actuating levers to exert thrusts by said actuating levers in opposite directions against said latch lever. 75

3. A reversible latch comprising a pivoted latch lever, two actuating levers pivoted 80 on the same pivot as the latch lever, one engaging each respective side of said latch lever, and spring means acting upon said actuating levers to cause them to exert thrusts in opposite directions against said latch lever. 85

4. A reversible latch comprising a pivoted latch lever, two actuating levers pivoted on the same pivot as the latch lever, one engaging each respective side of said latch lever, and a single spring interposed 90 between said actuating levers to cause them to exert thrusts in opposite directions against said latch lever. 95

5. A reversible latch comprising, a pivoted latch lever, a detent engageable with said latch lever when moved to a position at either side of central, a pivoted actuating lever engaging each respective side of said latch lever, and a single spring interposed 100 between said actuating levers to cause them to exert thrusts in opposite directions against the latch lever, said spring also engaging said latch lever to move it into engagement with said detent. 105

6. A reversible latch comprising a casing, a latch lever pivoted within the casing, two actuating levers pivoted on the same pivot as the latch lever and engaging opposite sides thereof, and spring means acting upon said actuating levers to cause them to exert thrusts in opposite directions against the latch lever, each actuating lever engaging the casing to limit its respective movement in one direction to a central normal position. 110

7. A reversible latch comprising a casing, a latch lever pivoted within the casing, two actuating levers pivoted on the same pivot as the latch lever and engaging opposite sides thereof, and a single spring interposed between said actuating levers to move them to exert thrusts in opposite directions against the latch lever, each actuating lever engaging the casing to stop its respective movement in one direction to a central normal position. 115

8. A reversible latch comprising a casing, a latch lever pivotally mounted in the casing, a detent engaged by said latch lever 120

125

130

- when moved to a position in either direction from central, two actuating levers pivoted within the casing and engaging opposite sides of the latch lever, and spring 5 means acting upon the actuating levers to cause them to exert thrusts in opposite directions against the latch lever and also acting upon the latch lever to move it into engagement with said detent, said actuating 10 levers engaging the casing to limit their respective movements in one direction to a central normal position.
9. A reversible latch comprising a casing, a latch lever pivotally mounted in the casing, a detent engaged by said latch lever and moved to a position in either direction from central, two actuating levers pivoted within the casing and engaging opposite sides of the latch lever, and a single spring interposed between said actuating levers and also engaging the latch lever to cause the actuating levers to exert thrusts in opposite directions against the latch lever and to move the latch lever into engagement with said 20 detent, said actuating levers engaging the casing to limit their respective movements in one direction to a central normal position.
10. A reversible latch comprising a casing, a latch lever pivotally mounted in the casing, a detent engaged by said latch lever and moved to a position in either direction from central, two actuating levers within the casing, both pivoted on the latch lever 25 pivot, and a single spring interposed between said actuating levers and also engaging the latch lever to cause the actuating levers to exert thrusts in opposite directions
- against the latch lever and to move the latch lever into engagement with said detent, said actuating levers engaging the casing to limit their respective movements in one direction to a central normal position. 40
11. A reversible latch comprising a pivoted latch lever, two actuating levers pivoted on the same pivot as the latch lever and each extending in both directions from the pivot longitudinally of the latch lever, said actuating levers engaging opposite sides of the latch lever at their rear extremities, a compression spring interposed between the forward extremities of the actuating levers and stop means to stop the movement of each actuating lever in one direction at a central normal position. 45 50 55
12. A reversible latch comprising a pivoted latch lever, a detent engageable with the latch lever when it is moved to a position in either direction from central, two actuating levers pivoted on the same pivot as the latch lever and extending in both directions from the pivot longitudinally of the latch lever, the rear extremities of the respective actuating levers engaging opposite sides of the latch lever, a compression spring interposed between the forward extremities of the actuating levers, said spring also engaging the latch lever to move it into engagement with said detent, and stops engaged by the actuating levers to stop their respective movements in one direction at a central normal position. 60 65 70

In testimony whereof we affix our signatures.
